LEVELING MACHINE

Fred V. Hart, Lynn, Mass., assignor to United
Shoe Machinery Corporation, Flemington, N. J.,
a corporation of New Jersey

Application November 1, 1947, Serial No. 783,542

28 Claims. (Cl. 312—34)

1

This invention relates to machines for operating upon shoes, and more particularly to machines for shaping or leveling the bottoms of shoes. The invention is illustrated herein with reference to that type of machine in which the bottom of a shoe is acted upon by a leveling roll, the roll being mounted for movements lengthwise of the shoe and for tipping movements transversely of the shoe bottom.

It is an object of the invention to provide an improved machine of the type referred to above in which movements of the roll lengthwise of the shoe bottom are effected by power-operated means which is in turn controlled by a manual operating member in such manner that the roll is moved into positions corresponding to the positions into which the operating member is moved by the operator. In accordance with a feature of the invention, the operating member is in the form of a pair of handles mounted at opposite ends of the roll but movable relatively thereto, the handles being arranged to be moved by the operator into positions corresponding to the positions to which it is desired to move the roll. The handles control the flow of pressure fluid to a fluid-pressure motor by which movements of the roll lengthwise of the shoe are effected, there being provision for cutting off the flow of pressure fluid to the motor upon movement of the roll to a position corresponding to that of the handles.

In accordance with a further feature of the invention, the handles are also mounted for tipping movements about an axis extending transversely of the axis of the leveling roll and the handles control, by their tipping movements, the flow of pressure fluid to a fluid-pressure-operated roll-tipping motor, there being provision for cutting off the flow of pressure fluid to this motor upon movement of the roll into a position corresponding to the position into which the handles have been moved. Thus, the operator, by manipulation of the two handles which are movable in unison, controls the movements of the roll both lengthwise of the shoe bottom and laterally thereof. Accordingly, the roll follows the movements of the handles, making control of the movements of the leveling roll by the operator very simple, the roll being manipulated over the shoe bottom in the manner of a rolling pin. The movements of the roll are, however, effected by power, thereby minimizing fatigue on the part of the operator in carrying out the leveling operation.

In accordance with a still further feature of

the invention, the leveling roll is forced by a fluid-pressure motor into engagement with the shoe bottom, the introduction of pressure fluid into the motor being controlled by one of the aforementioned operating handles. By a slight heightwise movement of the handle, the roll may be lifted from the shoe bottom or forced into engagement therewith. Thus, the operator has complete control at all times over all movements of the leveling roll.

Another object of the invention is to provide an improved leveling machine in which the leveling operation may be commenced either at the toe end of the shoe or at the heel end in accordance with the desires of the operator. This is accomplished, in accordance with a further feature of the invention, by providing a support for the shoe which may be turned into either of two positions in which the toe end of the shoe or the heel end thereof is directed rearwardly. Provision is made for locking the support in either of its two positions. With the toe end directed rearwardly, the leveling operation will start at the toe end, whereas it will start at the heel end when the heel end of the shoe is directed rearwardly. Associated with the shoe support, in accordance with another feature of the invention, is a motor by which a spindle on the heel-supporting member of the shoe support is rocked to force the toe end of the shoe against a toe post to support the shoe firmly for the action of the leveling roll.

The above and other features of the invention, including various novel details of construction and combinations of parts, will now be described by reference to the drawings and pointed out in the claims.

In the drawings,

Fig. 1 is a side elevation, partly in section, of the upper portion of one form of a machine in which the invention is embodied;

Fig. 2 is a view similar to Fig. 1, of the lower portion of the machine;

Fig. 3 is a detail view in side elevation of a portion of the mechanism for operating the pressure-regulating valve and the main control valve of the fluid-pressure system of the machine;

Fig. 4 is a front elevation, partly in section, of the upper portion of the machine;

Fig. 5 is a section on the line V—V of Fig. 1;

Fig. 6 is a plan view of a portion of the mechanism for moving the roll vertically into and out of contact with the work;

Fig. 7 is a detail view, partly in section, of a

portion of the mechanism for tipping the leveling roll;

Fig. 8 is a plan view of the handles for controlling movements of the leveling roll;

Fig. 9 is a section on the line IX-IX of Fig. 1, and

Fig. 10 is a plan view partly in section of the means for adjusting the heel and toe posts of the jack.

The main frame 10 of the machine carries a shoe support or jack 12 for supporting a shoe S for the action of a leveling roll 14. The roll 14 is mounted, as will be described, for movements lengthwise of the shoe on the support for tipping movements laterally of the shoe bottom and for heightwise movements relatively to the shoe so that pressure may be applied by the roll to the shoe bottom or the pressure relieved at will. The jack 12 is held stationary during the leveling operation but is so mounted that the shoe may be supported with either its toe end or its heel end directed rearwardly toward the leveling roll, as will be described. This permits the operator to start the leveling operation from either the toe end of the shoe or the heel end as he desires.

The jack 12 includes a toe post 16 which carries at its upper end a toe support 18 and a support 20 for the cone of the last. The jack also includes a heel post 22 to which is pivoted at 24 for swinging movements in directions lengthwise of the shoe a block 26 which carries a spindle 28 adapted to enter the thimble hole in the heel end of the last. The spindle 28 passes through an enlarged opening in a plate 30 also carried by the block 26, the plate being free to tip about an axis extending laterally of the shoe to adjust itself to the top face of the cone of the last. This plate and the toe support are constructed substantially as disclosed in Letters Patent of the United States 1,962,141, granted June 12, 1934, on an application of A. Eppler, and accordingly are not described herein in detail. The block 26 is arranged to be swung in a clockwise direction, as viewed in Fig. 1, after a shoe has been mounted in the jack thereby to press the toe end of the shoe firmly down upon the toe support 18, by mechanism to be described.

The toe and heel supports are mounted for movements toward and away from each other thereby to adjust the jack for shoes of different sizes. The lower ends of the toe and heel supports have laterally extending flanges 31, as shown in Fig. 4, and are carried for sliding movements lengthwise of the machine in a way formed in the top plate 32 of a turntable 36. Gibs 34 secured to the top of the plate 32 engage the upper surfaces of the flanges at the bottoms of the toe and heel posts to prevent vertical displacement of the posts from the slideway. The turntable 36 is rotatable on a circular support 38 secured to the top of the frame 10 and extending upwardly therefrom. The upper portion of the support 38 has an internal flange 40 which acts as a circular bearing for the turntable 36 in a circular guideway formed by the plate 32 and a plate 42 secured to the lower portion of the turntable, the construction being such as to maintain the turntable in place upon the support. The turntable is arranged to be maintained in either of two positions spaced 180° apart by a pin 44 passing through a hole in the upper portion of the support 38 and arranged to enter either of two holes 46 (Fig. 1) in the turntable. The pin 44 is provided at its forward end with spaced flanges 48 between which is received the forked

upper end of a lever 50 pivoted at 52 to the support 38 and urged by a spring 54 in a direction to move the locking pin 44 rearwardly into locking engagement with one of the holes 46. By exerting a rearward force on the lower end of the lever 50 the pin 44 is retracted whereupon the turntable may be rotated. As shown in Fig. 4, an angular groove 56 is formed in the turntable and connects the holes 46 but extends only half way around the turntable. The pin 44 rides in the groove 56 when retracted from the holes and prevents movement of the turntable except between predetermined limits defined by the holes. Consequently, the operator cannot rotate the turntable more than 180° in one direction. This is of importance as otherwise the pressure fluid connections to be hereinafter described might become fouled.

For adjusting the toe and heel posts toward and away from each other to accommodate shoes of different sizes, screws 58, 60 (Figs. 1 and 10) are threaded through the toe and heel posts respectively, and are provided at their outer ends with handles 62, 64. Secured to the inner ends 20 of the screws are bevel gears 66 which engage a bevel gear 68 journaled on a stud 70 carried by a post 72 secured to and extending upwardly from the turntable 36. It will be noted that the threads on the screws 58, 60 extend in the same directions but by virtue of the bevel gearing, above described, connecting the two screws, they will turn in opposite directions when either of them is rotated by manipulation of one of the handles 62, 64. Consequently, if the handle 64 is turned in a counterclockwise direction (Fig. 1) as viewed from the front of the machine, the heel post 22 will move forwardly and the toe post 16 will move rearwardly. If now the jack is turned through 180° so that the toe post is nearer the front of the machine and the handle 62 is convenient to the operator, rotation of this handle in a counterclockwise direction will produce the same result. This arrangement tends to avoid confusion to the operator when adjusting the relative positions 25 of the toe and heel posts in determining which direction to turn the handle which is accessible to him.

After the shoe is placed on the jack the block 26 is moved in a clockwise direction as viewed 30 in Fig. 1 in order to force the toe end of the shoe firmly against the toe support 18. For this purpose a fluid pressure motor comprising a cylinder 74 is pivoted at 76 to an extension of the lower end of the heel post 22. A piston 78 movable in the cylinder 74 is connected by a piston rod 80 to the lower end of a bell crank lever 82 pivoted at 84 to the heel post 22. This lever has an arm 86 which extends rearwardly, when the jack is positioned as shown in Fig. 1, for engagement with a pin 88 in the lower end 35 of a link 90, the upper end of which link is pivoted at 92 to the block 26. The pin 88 is connected by a link 94 to the lower end of an arm 96 of a second bell crank lever pivoted at 98 to the heel post. This latter bell crank lever has an arm 100 carrying a pawl 102 (Fig. 4) engageable with a ratchet 104 on the heel post, the arrangement being such that the bell crank lever 96, 100 may be held in any one of a plurality of positions of adjustment, permitting adjustment of the fulcrum about which the link 94 pivots when the bell crank lever 82 is rocked about the pin 84 to move the block 26 in a clockwise direction. By this adjustment the leverage through which 40 the pressure fluid acts is controlled thereby reg-

ulating the force with which the shoe is urged against the toe support when pressure fluid is admitted through a pipe 106 into the right end of the cylinder 14. The mechanism for supplying and controlling the admission of pressure fluid into the cylinder 14 will be explained hereinafter.

The leveling roll 14 is journaled in the forward end of a support 108 which is in turn pivotally connected by a pin 110 to a forwardly and rearwardly extending shaft 112, journaled in a cross-head 114. This crosshead is carried by transversely-extending shafts 116, 118, the shaft 116 being journaled in the upper ends of a pair of spaced arms 120 which are interconnected by webs 122, 124 (Figs. 1 and 2) to form a rigid structure. The arms 120 are secured to a shaft 126 journaled in brackets 128 extending upwardly from a plate 130 forming the top of a fluid reservoir 132 carried by the lower portion of the frame 10. The shaft 118 is similarly carried by a pair of spaced arms 134 interconnected by a web 136 and carried by a shaft 138 journaled in the brackets 128. It will be understood that as the pairs of arms 120, 134 are moved about the axes of the shafts 126, 138 the leveling roll will be moved lengthwise of a shoe on the jack 12. For thus moving the arms 120, 134 and the leveling roll, the arms 120 are connected by a link 140 (Fig. 2) to a piston 142 movable in a cylinder 144 pivoted at 146 within the frame of the machine. Upon admission of fluid under pressure through a pipe 148 into the cylinder 144 the piston 142 will move forwardly causing similar motion to be imparted to the leveling roll, and the roll will be moved rearwardly upon admission of pressure fluid through a pipe 150 into the forward end of the cylinder.

Provision is made for moving the leveling roll heightwise of the shoe on the support by rocking the roll support 108 about the pin 110. Extending upwardly from the support 108 is a pair of parallel curved arms 152 (Figs. 1 and 4) having slots 156 adjustably to receive a pin 158 carried by the forward end of a piston rod 158. This rod is connected to a piston 160 movable in a cylinder 162 pivoted at 164 to a supporting bracket 166 keyed to and extending upwardly from the rearward end of the shaft 112. Upon admission of pressure fluid through a pipe 168 into the rearward end of the cylinder 162, the piston 160 is moved forwardly thereby moving the roll support 108 downwardly about the pivot 110 causing movement of the roll toward the shoe bottom. To lift the roll out of engagement with the shoe bottom, fluid under pressure is admitted through a pipe 170 into the forward end of the cylinder 162 moving the piston 160 rearwardly. To vary the pressure exerted by the leveling roll on the shoe for a given movement of the piston 160 the position of the pin 158 can be adjusted heightwise of the arms 152.

Tipping movements are imparted to the roll by a fluid pressure motor 172 (Figs. 1 and 9) carried by a plate 174 extending downwardly from the crosshead 114. This motor includes a cylinder 176 pivotally secured at 178 to the plate 174 and a piston 180 movable vertically in the cylinder. An upwardly extending piston rod 182 is pivotally connected to an arm 184 extending laterally from the bracket 166 which is keyed to the shaft 112. It will be understood that upon introduction of fluid under pressure through a pipe 186 into the bottom of the cylinder 176 the piston 180 is forced upwardly moving the

arm 184 in a counterclockwise direction as viewed in Fig. 9 to tip the roll in the same direction. Reverse tipping of the leveling roll takes place upon the introduction of fluid under pressure into the upper end of the cylinder 176 through a pipe 188.

For supplying pressure fluid to the various motors heretofore described a pump 190 (Fig. 2) is mounted within the fluid reservoir 132. This pump is driven by a motor 192 carried by the top 130 of the reservoir and connected by a belt 194 to a pulley 196 on the shaft of the pump. The high pressure side of the pump is connected by a pipe 198 to a pressure-regulating valve 200 which may be similar to the pressure-regulating valve 246 illustrated and described in Letters Patent of the United States 2,230,244 granted February 4, 1941 on an application filed in the names of Fred V. Hart and John J. Austin. This valve includes a rod 202 which, when in its upper position, as illustrated in Fig. 2, permits fluid to flow from the pipe 198 directly back to the reservoir 132 by way of a pipe 204. However, when the rod 202 is moved downwardly by the straightening of a toggle 206 (Fig. 3) pressure fluid then flows through a pipe 208 into a valve 210. This valve includes a valve element 212 which, when in the position shown in Fig. 2, permits pressure fluid to exhaust from the various motors through a pipe 214 into a pipe 216 which discharges into the fluid reservoir. However, when this valve is turned in a clockwise direction through an angle of approximately 30° the pipe 214 communicates with the pipe 208 from the valve 200 by way of passageways 218, 220 within the valve. The valve member 212 is also provided with a port 221, the sole purpose of which is to balance the pressures exerted on the interior of the valve housing 210 to avoid sticking of the valve which might otherwise occur.

The toggle 206 (Fig. 3) includes a link 222 connected to the upper end of the rod 202 and an arm 224 connected to the valve element 212. When the toggle is straightened the arm 224 is turned in a clockwise direction moving the valve into position to connect the high pressure outlet pipe 208 of the valve 200 with the pipe 214. This occurs simultaneously with the operation of the pressure-regulating valve 200 to supply fluid under pressure to the pipe 208 and to prevent free discharge of the fluid through the pipe 204 back to the reservoir.

For straightening the toggle 206, mechanism illustrated in Fig. 2 is provided and includes a treadle 226 pivoted at 228 to a bracket depending from the bottom wall of the reservoir 132. This treadle is so arranged that upon one depression thereof the toggle 206 is straightened and upon the next depression thereof a spring 230 connected between the knee of the toggle and a pin 232 carried by the bracket 128 is effective to break the toggle. Extending forwardly from the knee of the toggle 206 is a rod 234 the forward end of which carries a latch member 236. Pivoted to this latch member is an arm 238 of a bell crank lever which is pivoted at 240 to a bracket secured to the top 130 of the reservoir. This bell crank lever has a forwardly extending arm 242 which, when the parts are in the positions shown in Fig. 2, is in the path of movement of a shoulder 243 formed at the upper end of an arm 244 which is pivoted at 246 to the treadle 226. The arm 244 is urged by a spring 248 into position to engage the arm 242 so that upon downward movement

of the treadle the bell crank lever 238, 242 is moved in a counterclockwise direction causing the rod 234 to move forwardly straightening the toggle 206. Pivoted to the frame of the machine below the latch member 236 is a latch bar 250 which is urged upwardly toward the latch member 236 by a spring 252 connecting the two. The latch bar 250 moves into locking engagement with the latch member 236 when the rod 234 is moved forwardly thereby locking the toggle in its straightened position. Upon release of the pressure on the treadle 226 it is returned into the position shown in Fig. 2 by a spring 254, this position being determined by an adjustable stop screw 256 which is engaged by the treadle. During this upward movement of the treadle the upper end of the arm 244 engages the forward end of the latch member 236 which is now in its forward position thereby causing the arm 244 to move in a counterclockwise direction against the action of a spring 248. Pivoted to the upper end of the arm 244 is a latch 256 urged for movement in a clockwise direction relatively to the arm 244 by a spring 258 the extent of such movement being limited by a pin 260 carried by the upper end of the arm. With the treadle in its upper position after the toggle has been straightened it will be understood that the arm 244 is held in a position forwardly of the machine from that shown in Fig. 2. When in this position the latch member 256 is located above a pin 262 carried by the forward end of the latch bar 250 and extending laterally therefrom so that upon the next depression of the treadle 226 the latch bar 250 is moved downwardly out of engagement with the latch member 236 permitting the rod 234 to be moved rearwardly by the spring 230 and returning the valves to the positions shown in Fig. 2. At this time the arm 244 is out of the path of movement of the arm 242 of the bell crank lever when the lever returns into the position shown. When the treadle is again released after the parts have been returned to their initial positions, the lower end of the latch 256 moves out of engagement with the pin 262 whereupon the spring 248 returns the arm 244 into the position shown, in readiness for the next operation.

Movements of the roll 14 during the leveling operation are controlled by a pair of handles 266, 268 (Figs. 4, 5 and 8) which are carried by a supporting frame 270 and are preferably located substantially in alignment with the axis of the leveling roll at opposite ends thereof. The handle 266 is rigidly carried by the supporting frame 270 and the handle 268 is carried for pivotal movement thereon about the axis of a stud 272 (Fig. 4) for a purpose to be described. The supporting frame 270 is pivoted on a block 274 (Fig. 5) for movements about a horizontal axis extending substantially parallel to the roll 14, the block in turn being secured to a splined shaft 276 journaled in a boss 278 carried by the roll support 108 and extending upwardly therefrom. The splined shaft 276 is slidable in a sleeve 280 formed with keys fitting the grooved portions of the shaft 276 so that the sleeve and shaft will turn in unison. The sleeve 280 is connected by a horizontal pivot pin 282 to a coupling member 284 which is in turn secured to a shaft 286 passing through a bearing sleeve 288 having a depending portion keyed to the roll-supporting shaft 112. It will be understood that upon heightwise movement of the leveling roll the splined shaft 276 will partake of a corresponding movement causing the heightwise position of the

handles 266, 268 always to correspond to that of the roll but at all times the shaft 276 to which the handles are connected, as heretofore described, is connected to the shaft 286 for a purpose which will appear as the description proceeds.

For controlling the admission of pressure fluid into the cylinder 144 (Figs. 1 and 2) thereby to control the movements of the leveling roll lengthwise of the shoe bottom, a valve 290 (Figs. 1 and 5) is provided and is carried by a plate 291 extending laterally from the roll support 108. This valve has a central port connected by pipes 292, 294 with the pipe 214 leading from the valve 210 and through which fluid under pressure passes when the toggle 206 (Fig. 3) is straightened. This valve may be constructed like the valve 234 of Patent No. 2,230,244, the arrangement being such that when the valve element is moved to the left, as viewed in Fig. 1, or forwardly of the machine, pressure fluid flows from the valve through the pipe 148 and when the valve is moved to the right or rearwardly of the machine the fluid leaves the valve through the pipe 150. However, when the valve is in a midposition the flow of pressure fluid through either of these pipes is prevented. Connected to the valve element is a forwardly extending rod 302 pivoted at 302 to the supporting frame 270. This rod carries collars 304, 306 forming abutments for compression springs 308 the adjacent ends of which engage collars 309 at opposite sides of a flange 310 extending downwardly from the plate 291, between which collars is a collar fixed to the rod. It will be understood that when the handles 266, 268 are moved forwardly by the operator the rod 302 will be similarly moved operating the valve 290 to cause pressure fluid to flow from the pipe 148 into the rear end of the cylinder 144 whereupon the leveling roll also moves forwardly. After the roll has moved forward a distance corresponding to the extent of movement of the handles the parts associated with the leveling roll will assume their relative positions shown in Fig. 1 so that the flow of fluid through the pipe 148 ceases. Upon rearward movement of the handles relatively to the roll pressure fluid flows through the pipe 150 into the forward end of the cylinder 144 causing the leveling roll likewise to move rearwardly. Thus it will be understood that forward and rearward movements of the leveling roll are caused by moving the handles 266, 268 forwardly and rearwardly, the extent and directions of movement of the roll corresponding to the extent and directions of movement of the handles. The leveling roll, however, is moved by fluid pressure so that the forward and rearward movements of the roll which are controlled by similar movements of the handles are effected with a minimum of effort on the part of the operator.

For controlling the flow of pressure fluid into the cylinder 162 (Fig. 1) for moving the leveling roll into and out of engagement with the shoe bottom a valve 312 is provided, this valve being similar in construction to the valve 290 and mounted on the top of the cylinder 162. The central portion of this valve is connected to the pipe 294 by a pipe 314 and the opposite ends of the valve are connected by the pipes 168, 170 to the opposite ends of the cylinder 162. The element of this valve is normally held in a forward position so that when the toggle 206 is straightened fluid pressure flows into the forward end of the cylinder 162 holding the roll in raised position. During the leveling operation the valve element

is moved rearwardly so that pressure fluid flows through the pipe 168 to move the leveling roll into engagement with the work. The valve includes a valve stem 316 (Fig. 6) connected by a bar 318 with the armature 320 of a solenoid 322 carried by the cylinder 162 adjacent to the valve 312. A spring 324 acts on the bar 318 normally to hold the valve stem 316 in its forward position. Upon energization of the solenoid, however, the armature 320 is drawn inwardly operating through the bar 318 to move the valve stem 316 rearwardly so that pressure fluid flows behind the piston 160 and the leveling roll is forced against the shoe bottom. For energizing the solenoid a switch 326 (Fig. 4) is mounted on the supporting frame 270 and is arranged to be actuated by an arm 328 connected to the handle 268 when the handle is moved about the pivot 272 in a counterclockwise direction, thereby to close the circuit to the solenoid. An adjustable stop screw 330 limits the extent of movement of the handle 268 in switch-closing direction and the handle is normally held in the position shown relatively to the frame 270 by a torsion spring 332. Thus it will be seen that in order to force the leveling roll against the shoe bottom after it has been moved over the shoe bottom as heretofore described, it is necessary for the operator merely to apply slight downward pressure to the handle 268 closing the switch 326 and energizing the solenoid 322. At any time during the leveling operation that the operator desires to lift the leveling roll he need only relieve the downward pressure on the handle 268 whereupon the switch 326 is opened and the solenoid is deenergized.

For controlling the tipping movements of the leveling roll which are effected by movements of the piston 180 (Fig. 9) a valve 334 is provided which may be similar to the valve 290. The central portion of this valve is connected by a pipe 336 to the pipe 294 (Figs. 1 and 2) which is in turn connected to the outlet of the valve 210. The opposite ends of the valve 334 are connected by the pipes 186, 188 to the opposite ends of the cylinder 176. The valve includes an upwardly projecting valve-operating rod 338 pivoted to one end of a lever 340 the other end of which is connected by a pin 341 to a link 342. This link connects the lever 340 to a lever 344 which is in turn pivoted at 346 to a bracket projecting rearwardly from the plate 174 (Figs. 1 and 7). The lever 340 (Fig. 9) has pivoted to it at 339 a link 348 the upper end of which is pivoted to an arm 350 secured to the shaft 286 which is in turn connected to the handle-supporting frame 270 as heretofore described. The lever 344 is connected by a link 352 to an arm 354 integral with the arm 184 by which movements of the piston 180 cause tipping movements of the leveling roll.

Whenever during the leveling operation the operator desires to tip the leveling roll he exerts pressure on one of the handles 266, 268 to rock the frame 270 in the direction of the desired roll-tipping movement. This movement of the handle-supporting frame 270 is communicated through the shafts 276, 286, arm 350 (Fig. 9), link 348 and lever 340 to move the valve rod 338 in one direction or the other according to the direction of movement of the handle-supporting frame. Assume that the shaft 286 is moved in a counterclockwise direction, the lever 340 will move downwardly about the pivot 341 to move the valve-actuating rod 338 downwardly whereupon pressure fluid flows into the bottom of the cylinder 176 to move the piston upwardly and rock the

shaft 112 in a counterclockwise direction, so that the leveling roll follows the movement of the handles in its tipping movement. The tipping movement of the roll will continue until it has moved into a position corresponding to the positions of the handles at which time the roll-tipping movement ceases. During the tipping movement of the roll the lever 344 moves downwardly assuming that the shaft 286 has been turned in a counterclockwise direction by movement of the frame 270 whereupon the lever 340 moves about the pivot 339 to move the valve back toward its mid-position. When the roll has moved an amount corresponding to the extent of movement of the handles the valve again returns to its midposition so that the roll-tipping movement stops. It will be understood that if the shaft 286 is rocked in a clockwise direction the roll will be tipped in a corresponding direction, the piston 180 at this time moving downwardly.

In the operation of the machine, the operator places a shoe on the jack, after the jack has been properly adjusted in accordance with the size of the shoe to be leveled, whereupon the treadle 226 is depressed to straighten the toggle 206 and pressure fluid flows into the right end of the cylinder 74 (Fig. 1) to tip the block 26 in a clockwise direction forcing the toe end of the shoe firmly down against the toe support 18. The operator then grasps the handles 266, 268 moving them toward him which causes operation of the valve 290 to supply pressure fluid to the cylinder 144 thereby to move the roll over the shoe bottom. By exerting slight downward pressure on the handle 268 the solenoid 322 is energized operating the valve 312 (Fig. 6), and pressure fluid flows into the rear end of the cylinder 162 (Fig. 1) forcing the roll against the shoe bottom. The roll is now moved lengthwise of the shoe by moving the handles 266, 268 toward and away from the operator in the manner of operating a rolling pin. By exerting pressure on one or the other of the handles and tipping the handle-supporting frame 270, the valve 334 is operated to supply pressure fluid into one end or the other of the cylinder 176 (Fig. 9) causing the roll to tip accordingly.

After the leveling operation has been completed the leveling roll is returned to the position shown in Fig. 1 and the treadle 226 is again depressed, releasing the latch 236 whereupon the toggle 206 is broken by the spring 230 and the valve element 212 is returned to the position shown in Fig. 2. At the same time the pressure-regulating valve is operated to permit the fluid flowing from the pump 190 to return directly to the reservoir.

From the foregoing it will be seen that the handles 266, 268 are manipulated by the operator in precisely the manner in which he wishes the roll to move. Since the handles merely control the operation of valves, little effort is required to move the handles and the work of moving the leveling roll in accordance therewith is all done by fluid pressure. The roll will always move into a position corresponding to the positions of the handles during the leveling operation so that the roll remains with its axis substantially in alignment with the axis of the handles.

Having thus described the invention what I claim as new and desire to secure by Letters Patent of the United States is:

1. In a leveling machine, a shoe support, a leveling roll mounted for movements lengthwise of a shoe on the support to cause the roll to operate progressively along the shoe bottom, power-operated means for thus moving said roll, and a

member movable by the operator for controlling said power-operated means to cause it to move said roll into positions corresponding to the positions into which said member is moved by the operator.

2. In a leveling machine, a shoe support, a leveling roll mounted for movements lengthwise of a shoe on the support to cause the roll to operate progressively along the shoe bottom, power-operated means for thus moving said roll, and a member mounted adjacent to said roll for movements by the operator lengthwise of a shoe on the support for controlling said power-operated means to cause the roll to follow the movements of said member.

3. In a leveling machine, a shoe support, a leveling roll mounted for movements lengthwise of a shoe on the support to cause the roll to operate progressively along the shoe bottom and also for tipping movements laterally of the shoe bottom, power-operated means for moving said roll lengthwise of the shoe, power-operated means for imparting tipping movements to said roll, and a control member movable along one path for controlling the first of said power-operated means and movable along another path for controlling the second of said power-operated means.

4. In a leveling machine, a shoe support, a leveling roll mounted for movements lengthwise of a shoe on the support to cause the roll to operate progressively along the shoe bottom and also for tipping movements laterally of the shoe bottom, power-operated means for moving said roll lengthwise of the shoe, power-operated means for imparting tipping movements to said roll, and a control member movable lengthwise of the shoe on the support for controlling the first of said power-operated means to cause the roll to move into positions lengthwise of the shoe on the support corresponding to the positions into which said member is moved by the operator, and movable laterally of the shoe on the support to control the second of said power-operated means to cause the roll to tip into positions corresponding to the positions into which said member is moved laterally of the support.

5. In a leveling machine, a shoe support, a leveling roll mounted for movements lengthwise of a shoe on the support to cause the roll to operate progressively along the shoe bottom and also for tipping movements laterally of the shoe bottom, power-operated means for moving said roll lengthwise of the shoe, power-operated means for imparting tipping movements to said roll, a control member movable lengthwise of the shoe on the support for controlling the first of said power-operated means to cause the roll to move into positions lengthwise of the shoe on the support corresponding to the positions into which said member is moved by the operator, and movable laterally of the shoe on the support to control the second of said power-operated means to cause the roll to tip into positions corresponding to the positions into which said member is moved laterally of the support, and means operated by said member for moving the roll heightwise of the shoe bottom.

6. In a leveling machine, a shoe support, a leveling roll mounted for movements lengthwise of a shoe on the support to cause the roll to operate progressively along a shoe bottom, a pair of operating handles near the opposite ends of said roll, means mounting said handles for unitary movements by the operator in directions lengthwise of the shoe on the support, and power-

operated means controlled by said handles for causing said roll to follow the movements of the handles.

7. In a leveling machine, a shoe support, a leveling roll mounted for movements lengthwise of a shoe on the support to cause the roll to operate progressively along a shoe bottom, a pair of operating handles near the opposite ends of said roll, means mounting said handles for unitary movements by the operator in directions lengthwise of the shoe on the support, power-operated means controlled by said handles for causing said roll to follow the movements of the handles, and means controlled by one of said handles for causing the roll to be moved vertically toward and away from the shoe bottom.

8. In a leveling machine, a shoe support, a leveling roll mounted for movements lengthwise of a shoe on the support to cause the roll to operate progressively along the shoe bottom, a pair of operating handles near the opposite ends of the rolls, means mounting said handles for unitary movement by the operator in directions lengthwise of the shoe on the support and also for unitary rocking movements laterally of the shoe on the support, power-operated means for moving the roll lengthwise of the shoe on the support, power-operated means for tipping the roll laterally of the shoe on the support, and means for operating both of said power-operated means in response to movements of the handles by the operator whereby the roll is moved into positions corresponding to the positions of the handles relatively to the shoe on the support.

9. In a leveling machine, a shoe support, a leveling roll mounted for movements lengthwise of a shoe on the support to cause the roll to operate progressively along the shoe bottom, a pair of operating handles near the opposite ends of the rolls, means mounting said handles for unitary movement by the operator in directions lengthwise of the shoe on the support and also for unitary rocking movements laterally of the shoe on the support, power-operated means for moving the roll lengthwise of the shoe on the support, power-operated means for tipping the roll laterally of the shoe on the support, means for operating both said power-operated means in response to movements of the handles by the operator whereby the roll is moved into positions corresponding to the positions of the handles relatively to the shoe on the support, and means controlled by one of said handles for causing the roll to be moved vertically toward and away from the shoe bottom.

10. In a leveling machine, a shoe support, a leveling roll, means mounting said leveling roll for movements lengthwise of a shoe on the support to cause the roll to operate progressively along the shoe bottom, fluid pressure means for thus moving said roll, and means associated with said roll for controlling said fluid pressure means.

11. In a leveling machine, a shoe support, a leveling roll, means mounting said leveling roll for movements lengthwise of a shoe on the support to cause the roll to operate progressively along the shoe bottom, fluid pressure means for thus moving said roll, an operating member at one end of said roll mounted for movements by the operator in directions lengthwise of a shoe on the support, and mechanism operated by said member for controlling said fluid pressure means to cause the roll to follow the movements of said member.

12. In a leveling machine, a shoe support, a

leveling roll, means mounting said leveling roll for movements lengthwise of a shoe on the support to cause the roll to operate progressively along the shoe bottom, fluid pressure means for thus moving said roll, an operating member at one end of said roll mounted for movements by the operator in directions lengthwise of a shoe on the support, mechanism operated by said member for controlling said fluid pressure means to cause the roll to follow the movements of said member, and fluid pressure means controlled by said member for moving said roll heightwise of the shoe on the support into and out of engagement with the shoe bottom.

13. In a leveling machine, a shoe support, a leveling roll, means mounting said leveling roll for movements lengthwise of a shoe on the support to cause the roll to operate progressively along the shoe bottom, fluid pressure means for thus moving said roll, an operating member at one end of said roll mounted for movements by the operator in directions lengthwise of a shoe on the support, mechanism operated by said member for controlling said fluid pressure means to cause the roll to follow the movements of said member, fluid pressure means controlled by said member for moving said roll heightwise of the shoe on the support into and out of engagement with the shoe bottom, and other fluid pressure means controlled by said member for imparting tipping movements to the roll laterally of the shoe bottom.

14. In a leveling machine, a shoe support, a leveling roll, a support for said leveling roll, power-operated means for moving said roll support to move the leveling roll in directions lengthwise of a shoe on the shoe support to cause the roll to operate progressively along the shoe bottom, and power-operated means associated with said roll support for tipping the leveling roll laterally thereof.

15. In a leveling machine, a shoe support, a leveling roll, a support for said leveling roll, power-operated means for moving said roll support to move the leveling roll in directions lengthwise of a shoe on the shoe support to cause the roll to operate progressively along the shoe bottom, power-operated means associated with said roll support for tipping the leveling roll laterally thereof, and operating handles associated with said roll for controlling each of said power-operated means.

16. In a leveling machine, a shoe support, a leveling roll, a support for said leveling roll, power-operated means for moving said roll support to move the leveling roll in directions lengthwise of a shoe on the shoe support to cause the roll to operate progressively along the shoe bottom, and power-operated means associated with said roll support for moving the leveling roll heightwise into and out of engagement with the bottom of a shoe on the support.

17. In a leveling machine, a shoe support, a leveling roll, a support for said leveling roll, power-operated means for moving said roll support to move the leveling roll in directions lengthwise of a shoe on the shoe support to cause the roll to operate progressively along the shoe bottom, power-operated means associated with said roll support for moving the leveling roll heightwise into and out of engagement with the bottom of a shoe on the support, and operating handles associated with said roll for controlling each of said power-operated means.

18. In a leveling machine, a shoe support, a

leveling roll, a support for said leveling roll, power-operated means for moving said roll support to move the leveling roll in directions lengthwise of a shoe on the shoe support to cause the roll to operate progressively along the shoe bottom, power-operated means associated with said roll support for tipping the leveling roll laterally thereof, power-operated means associated with said roll support for moving the leveling roll heightwise into and out of engagement with the bottom of a shoe on the support, and an operating handle associated with said roll for controlling each of said power-operated means.

19. In a leveling machine, a shoe support, a leveling roll, a support for said leveling roll movable to carry the roll in directions lengthwise of a shoe on the shoe support, means mounting said roll on said roll support for tipping movements relatively thereto in directions laterally of a shoe on the shoe support and for movements heightwise of the shoe support toward and away from the shoe bottom, power-operated means for moving said roll support, and power-operated means movable with said roll support for tipping the roll.

20. In a leveling machine, a shoe support, a leveling roll, a support for said leveling roll movable to carry the roll in directions lengthwise of a shoe on the shoe support, means mounting said roll on said roll support for tipping movements relatively thereto in directions laterally of a shoe on the shoe support and for movements heightwise of the shoe support toward and away from the shoe bottom, power-operated means for moving said roll support, power-operated means movable with said roll support for tipping the roll, a pair of operating handles movably carried by said support at opposite ends of said roll, and means operated in response to movement of said handles in the desired direction of roll movement for controlling said pressure-operated means to cause movement of the roll in the direction of movement of the handles.

21. In a leveling machine, a shoe support, a leveling roll, a support for said leveling roll movable to carry the roll in directions lengthwise of a shoe on the shoe support, means mounting said roll on said roll support for tipping movements relatively thereto in directions laterally of a shoe on the shoe support and for movements heightwise of the shoe support toward and away from the shoe bottom, power-operated means for moving said roll support, power-operated means movable with said roll support for tipping the roll, a pair of operating handles movably carried by said support at opposite ends of said roll, means operated in response to movement of said handles in the desired direction of roll movement for controlling said pressure-operated means to cause movement of the roll in the direction of movement of the handles, said last named means being constructed and arranged to limit the extent of operation of said power-operated means and the movement of said roll in accordance with the extent of movement of the operating handles.

22. In a leveling machine, a shoe support, a leveling roll, means for effecting relative movement of said shoe support and said leveling roll in directions lengthwise of a shoe on the support to cause the roll to operate progressively along the shoe bottom, and means mounting said shoe support for turning movement whereby a shoe carried thereby has either its toe end or its heel end directed rearwardly.

23. In a leveling machine, a shoe support, a

leveling roll, means for effecting relative movement of said shoe support and said leveling roll in directions lengthwise of a shoe on the support to cause the roll to operate progressively along the shoe bottom, means mounting said shoe support for turning movement, and means for locking said support in either of two positions in which either the toe end of a shoe carried thereby or the heel end of the shoe is directed rearwardly.

24. In a leveling machine, a shoe support, a leveling roll, means mounting said leveling roll for movement, from an initial position in which it is located rearwardly of a shoe on the support, in directions lengthwise of the shoe to cause the roll to operate progressively along the shoe bottom, and means mounting said shoe support for turning movement into either of two positions in which either the toe end of the shoe or its heel end is directed rearwardly.

25. In a leveling machine, a shoe support, a leveling roll, means for effecting relative movements of said shoe support and said leveling roll in directions lengthwise of a shoe on the support to cause the roll to operate progressively along the shoe bottom, said shoe support comprising a toe support and a heel support, said heel support including a spindle arranged to enter the hole in the heel end of a last, means mounting said spindle for rocking movement about an axis extending transversely of a shoe on the shoe support, and power-operated means for moving said spindle about said axis in a direction to force the toe end of the shoe firmly against the toe support.

26. In a leveling machine, a shoe support, a leveling roll, means for effecting relative movement between said shoe support and said leveling roll in directions lengthwise of a shoe on the support to cause the roll to operate progressively along the shoe bottom, said shoe support including a spindle arranged to enter the hole in the heel end of a last, means mounting said spindle for rocking movement about an axis extending transversely of a shoe on the shoe support, means mounting said shoe support for turning movement into either of two positions in which either the toe end of the shoe or its heel end is directed rearwardly, and power-operated means carried by said support for moving said spindle about said axis in a direction to force the toe end of the shoe firmly against the toe support.

wardly, and power-operated means carried by said support for moving said spindle about said axis in a direction to force the toe end of the shoe firmly against the toe support.

27. In a leveling machine, a shoe support, a leveling roll, means for effecting relative movement of said shoe support and said leveling roll in directions lengthwise of a shoe on the support to cause the roll to operate progressively along the shoe bottom, said shoe support comprising a toe support and a heel support, means for adjusting said toe support and said heel support toward and away from each other to accommodate shoes of different sizes, means carried by said heel support for forcing the toe end of the shoe firmly against the toe support, and power-operated means movable with the toe support for actuating said last-named means.

28. In a leveling machine, a shoe support, a leveling roll, fluid pressure means for effecting relative movement of said shoe support and said leveling roll in directions lengthwise of a shoe on the support to cause the roll to operate progressively along the shoe bottom, fluid pressure means associated with said shoe support for holding the shoe firmly on the shoe support, a pump for supplying pressure fluid to said fluid pressure means, a pressure-regulating valve controlling the output of said pump, a valve for controlling the flow of pressure fluid from said pressure-regulating valve to said first-named fluid pressure means, a valve for controlling the flow of pressure fluid from said pressure-regulating valve to said second-named fluid pressure means, an actuating member for operating said second-named valve to direct pressure fluid to said second-named fluid pressure means and for simultaneously actuating said pressure-regulating valve to supply fluid at a high operating pressure to said first flow control valve, and a manually-operated member for controlling said first valve to control the relative movements of said shoe support and said leveling roll.
